UNITED STATES PATENT OFFICE.

JOHN G. SCHMIDT, OF PHILADELPHIA, PENNSYLVANIA.

RAMMER FOR STREET-PAVING.

SPECIFICATION forming part of Letters Patent No. 350,700, dated October 12, 1886.

Application filed October 15, 1884. Serial No. 145,618. (No model.)

To all whom it may concern:

Be it known that I, JOHN G. SCHMIDT, of the city and county of Philadelphia, in the State of Pennsylvania, have invented certain new and useful Improvements in Rammers for Street-Paving, of which improvements the following is a specification.

My invention relates to that class of rammers for street-paving in which a series of weights or stamps are actuated by certain novel mechanical means for the compact and uniform ramming of cobble-stones or blocks laid between car-tracks or other roadways.

The objects of my invention are, first, to provide for the more efficient and expeditious ramming of the cobble-stones or Belgian blocks laid between car-tracks or other roadways, whereby greater solidity and uniformity of surface of street-paving are obtained, and, second, to provide certain mechanical means whereby any desired amount of curvity may be given to the street or roadway; and it consists in the peculiar construction and arrangement of the parts, hereinafter more particularly described.

To more clearly understand my invention, reference will be had to the accompanying drawings, forming part hereof, in which—

Figure 1 is an end elevation of my improved ramming-machine. Fig. 2 is a vertical longitudinal section of the machine on the line *x y* of Fig. 1. Fig. 3 is an enlarged detached view of one of the rammers, showing the operative parts thereof. Fig. 4 is a similar view of the same rammer in the automatically-locked and inoperative position it assumes when the portion of the surface acted upon by it has been rammed down to the required line or depth.

Similar letters of reference indicate like parts throughout the several views.

The frame-work of the machine is represented as a wooden structure, which consists of four longitudinal pieces, *a a*, four cross-pieces, *a' a'*, and four uprights, *b b*. To the under side of the frame-work suitable journals, *A A*, are secured for the reception of the axles *B B*, to which are attached the flanged wheels *C C*, fitting the gage of the rails, the whole forming a car or truck which may be easily moved

along the car-tracks or lifted therefrom in any convenient manner.

D D D are the rammers, fitted with working-rods *d d d*. There are seven of these rammers shown in Fig. 1 of the drawings arranged transversely in a row, with their faces covering the surface from rail to rail; but of course it will be understood that the number of rammers may be varied at will.

Two additional cross-pieces, *a²* and *a³*, are provided upon the main frame for guiding the rods *d d d*. The lifting of these rods and rammers is effected by means of a series of revolving double-armed lifters, *c e e*, so arranged upon the shaft *E* as to cause the actuation of the rammers, by means of the tappets *d' d' d'*, in rotation, each rammer striking two blows for every entire revolution of the driving-shaft *E*, which has its bearing in the main frame at *e' e'*, as shown in Fig. 1, and carries a fly-wheel, *E'*, at each end. Both of these wheels are fitted with suitable crank-handles, *e² e³*, for revolving the shaft by steam or other suitable motor-power when convenient.

The mechanism by which the desired amount of curvity, uniformity, and solidity in the pavement between the car-tracks is accomplished, which, however, constitutes the most important feature of my present invention, is constructed, by preference, in the following manner: Each rammer-rod *d*, above the guide-piece *a²*, Figs. 3 and 4, is provided with an adjustable collar, *f*. This collar *f* strikes and depresses a spring, *g*, when (after a series of blows upon the surface under operation) the face of the rammer has descended to the limit of adjustment, or, in other words, when the respective portions of the pavement have been rammed down to the exact line or depth desired. The depression of the spring *g* liberates, as is clearly shown in Figs. 3 and 4, a double-armed lever, *h*, vibrating in a fulcrum, *i*, secured to the frame-piece *d*. This lever *h* actuates at its lower extremity a sliding stop, *j*, above which a spiral spring, *k*, is so applied as to move the lever *h* into the position shown in Fig. 4 whenever its hooked upper end is liberated from the spring *g*, as above described.

The operation of the mechanism is as fol-

lows: When the parts *g*, *h*, and *j* are in the position shown in Fig. 3—that is, until the surface undergoing the ramming operation reaches the desired line of curvity or amount of depression—the rammer-rod *d* meets with no obstruction to its vertical movement, the tappet *d'* passes clear of the stop *j* near the upper extent of its stroke, and as soon, however, as the limit of depression of the surface under action is reached, and the collar *f* strikes the spring *g*, the latter is slightly depressed, thereby liberating the lever *h*. This lever *h*, through the action of the spiral spring *k*, releases it from the spring *g*, as shown in Fig. 4, and thereby causing the inner end of the sliding stop *j* to move in the direction of the rod *d*, and its tappet *d'* at the next movement of the rammer to be locked in its highest position, thereby suspending this rammer and keeping it inactive until the respective rammers in the series have performed their work, when the truck or car is moved along over a new space or field, on which its ramming machinery commences anew in a similar manner as above described. By a partial revolution of a light rock-shaft, *l*, extending across the frame in front of levers *h h*, the entire series of levers is pressed inward by a corresponding number of cams, *m m*, which cause the series of levers *h h* to be brought simultaneously into the position shown in Fig. 3, in which position they are held during the next operation by the springs *g g* until again successively liberated by the respective collars *f f*.

It will be readily understood that the posi-

tion of each collar *f* in the series relative to its hammer-face determines the limit of the downward movement of each rammer, and hence becomes the easy and reliable means for adjusting the series of rammers in the machine for any amount of curvature to be given to the surface of the pavement, which may be more or less rounded between the rails or straight or even concave, if so desired.

I am aware that ramming-machines have been constructed with a series of vertically moving rammers actuated by lifters and tappets, and hence I do not wish to be understood as claiming, broadly, such a combination; but

What I do claim as new, and desire to secure by Letters Patent, is—

1. In a ramming-machine for street-paving, the combination, with the rammer *D*, provided with rod *d*, having adjustable collar *f* and tappet *d'* thereon, of the shaft *E* and double-arm lifters *e*, so arranged that each rammer delivers two blows each revolution of the shaft *E*, substantially as described.

2. In a ramming-machine for street-paving, the combination, with the rammer *D*, provided with working-rod *d*, having adjustable collar *f* and tappet *d'* thereon, of the lever *h*, fulcrum *i*, rock-shaft *l*, cam *m*, springs *g k*, and sliding stop *j*, all arranged substantially as and for the purposes described.

JOHN G. SCHMIDT.
